ABSTRACT OF THE DISCLOSURE

A shampoo hat having a generally annular upstanding wall of a suitable height defining the central hole enabling it to be placed upon the head of an infant or other user. A brim formed integrally with the wall includes alternate ridges and grooves which extend radially from the base portion of the wall, and in one form extend only to midway of the brim. The wall and brim are molded of a foamed synthetic resin of cellular type into a unitary structure.

The present invention relates to an improvement in a shampoo hat which primarily is intended for use with the head of an infant when the infant is given a shampoo and which provides a partition between the head and the face so as to prevent shampoo and washing water from running down the face or from entering the eyes, ears or mouth.

The type of shampoo hat conventionally known and available has a brim which comprises an annular metal frame along its outer periphery and a rubber or vinyl resin sheet extending between the outer frame and an elastically expandable center hole which fits around the head. Accordingly, such shampoo hat is relatively heavy and when worn the hat causes much pain to the skin of the head which is in engagement with the peripheral edge of the hole, because it exerts undue pressure on the skin in linear contact therewith. Infants are therefore reluctant to wear it. In the case of other prior art shampoo hat provided with a rubber or vinyl resin brim, in addition, there is a need to secure a frame member to the outer edge of the brim in order to keep the brim taut, so that when the head is inserted into the center hole forming member which is formed substantially in circular shape, the strain thereby produced inevitably results in large sidewise wrinkles in the brim between the frame and the center head hole in accordance with the amount of the strain, thus impairing the natural flow and drainage of the shampoo or washing water on the brim surface. Furthermore, the conventional shampoo hat has another disadvantage that it is not suitable for mass production because of structural reasons and therefore it is costly and less suitable for popular use.

An important object of the present invention is to provide a shampoo hat mainly for infants which is made of a highly elastic foamed synthetic resin material and which is therefore extremely lightweight and capable of providing the desired comfortable partition between the head and the face with high degree of reliability but without imparting uncomfortable pressure to one's head when worn.

Another object of the present invention is to provide a shampoo hat which is so formed in its structure and material as to absorb the strain in the head inserting hole produced when it is worn and to thereby preclude the formation of sidewise wrinkles in the brim which would prevent the outflow of shampoo or the like, satisfactory drainage thus being ensured.

Still another object of the present invention is to provide a shampoo hat whose constituent parts are integrally molded of a foamed synthetic resin thereby providing amenability to mass production and low cost.

2

The shampoo hat of the present invention is made of a highly elastic, lightweight, foamed material of cellular type which is obtained by foaming a synthetic resin such as polyethylene. The present shampoo hat comprises a 5 wall formed substantially in circular or elliptical shape to define a central hole to be fitted around the user's head and extending upward to a suitable height, and further having a brim formed of a plurality of interjoined V-shaped parts extending radially from the base portion of 10 the wall, with the adjacent V-shaped parts constituting the main portion of the brim, and the wall and the brim being formed integrally.

In accordance with the present invention, the head-engaging wall made of a foamed synthetic resin when 15 brought into surface-to-surface contact with the side portion of the user's head during use is such that the hat imparts no undue pressure or gives hardly any clamping feeling to the head. This is also attributable to the fact that the material itself is highly elastic and comfortable 20 to the touch. In addition, the alternate ridges and grooves which may be provided at least in the upper surface of the brim in accordance with the present invention and which extend to the outer peripheral edge thereof serve to keep the brim taut and ensure satisfactory outflow of shampoo 25 or washing water. Thus the washing liquid can reliably be prevented from running down the face.

For better understanding of the present invention, an embodiment thereof will hereinafter be described with reference to the accompanying drawings, in which:

30 FIG. 1 is a plan view of a shampoo hat in accordance with the present invention;

FIG. 2 is a front view partly in section taken along the line 2—2 in FIG. 1;

FIG. 3 is a perspective view of the shampoo hat as it is 35 worn on the head of an infant; and

FIGS. 4, 5 and 6 are fragmentary essentially cross-sectional views, similar to FIG. 2, but depicting various alternative forms.

A shampoo hat of the present invention shown in FIGS. 40 1 to 3 is molded of a foamed material of cellular type made of a synthetic resin such as polyethylene. In order to 45 secure a snug fit but pressure-free contact with the heads of different sizes and shapes, the shampoo hat is provided with an upright, endless wall 2 defining a hole 1 for receiving the head and extending upward to a suitable height. The hole 1 may be in generally circular or elliptical form which has the longer diameter in the front-to-back direction of the head when the hat is put on the head. The 50 brim 3 which extends outward from the base portion of the wall 2 is provided, at least in its upper surface, with a plurality of V-shaped grooves 4 extending radially up to the outer peripheral edge of the brim 3. The wall 2 and the brim 3 are molded into a unitary structure.

Besides various advantages already described, the shampoo hat of this invention as described in the present mode of embodiment is advantageous in that there is no need to provide a frame member along the peripheral edge of the brim and that the deformation of the hole 1 to be produced when the hat is put on can be fully compensated for by the amenability of the foamed material which extends from the wall 2 to the peripheral edge of the brim 3, whereby folds or sidewise wrinkles to be otherwise formed in the brim can be precluded perfectly.

In accordance with FIG. 6 of the drawing, the grooves 65 in the shampoo hat of the present invention may alternatively be formed in the shape of a series of circular arches in section, namely in wavelike shape. The pitch of the grooves may be great or small as desired.

Further, the grooves which are to be positioned around 70 the forehead when the hat is put on may be so constructed as to be discontinued midway between the wall and the outer edge of the brim, whereby the washing liquid can

be guided to the grooves in the rear portion for drainage.

Although the present invention is described above with respect to a principal embodiment, such mode of embodiment is given merely for illustrative purpose but with no intent of limiting the scope of the invention. It will be apparent for those skilled in the art that various modifications of the invention can be made, but these modifications should be included in the scope of the present invention insofar as they do not depart from the claims below.

What is claimed is:

1. A one-piece shampoo hat formed of a molded foam synthetic material and free of any auxiliary supporting means embedded within said material, comprising a generally annular brim having an inner edge defining a generally centrally located hole for fitting the hat around a user's head, said brim having a plurality of grooves of predetermined shape emanating radially from said center hole edge and formed at least in the upper surface of said brim, and wherein said grooves extend only to and terminate approximately at an area midway between the center hole edge and the outer edge of said brim.

2. A one-piece shampoo hat as defined in claim 1 wherein said grooves are of a generally V-shaped cross-section, and have adjacent portions of the grooves joining with one another.

3. A one-piece shampoo hat as defined in claim 1 wherein an upwardly extending wall is provided along the inner peripheral edge of said brim for wear-engagement with the wearer's head when in use.

4. A one piece shampoo hat as defined in claim 1

wherein said central hole is of generally elliptical shape having the longer dimension in a front-to-back direction when applied to a user's head.

5. A one piece shampoo hat as defined in claim 1 wherein said grooves are comprised of a series of alternating arches having a wave-like shape.

6. A one-piece shampoo hat formed of a molded foam synthetic material and free of any auxiliary supporting means embedded within said material, comprising a generally annular brim having an inner edge defining a generally centrally located hole for fitting the hat around a user's head, said brim having a plurality of grooves of predetermined shape formed radially at least in the upper surface of said brim, and wherein said grooves extend primarily from approximately midway between said central hole edge and the outer edge of said brim.
